FIG. 7.

UNITED STATES PATENT OFFICE.

JAMES H. BLESSING, OF ALBANY, NEW YORK.

REVOLUBLE JOINT FOR SCREW VALVE-STEMS.

SPECIFICATION forming part of Letters Patent No. 315,464, dated April 14, 1885.

Application filed July 1, 1884. (No model.)

To all whom it may concern:

Be it known that I, JAMES H. BLESSING, of the city and county of Albany, in the State of New York, have invented new and useful 5 Improvements in Revoluble Joints for Screw Valve-Stems, of which the following is a full and exact description, reference being had to the accompanying drawings, which form part of this specification, and in which—
10 Figure 1 is a side elevation of the screw-stem and valve connected and secured together; Fig. 2, a like elevation with the filling-in piece and spring-clamp removed; Fig. 3, a horizontal section at the line $x-x$ of Fig. 15 1. Figs. 4 and 5 are respectively a plan view and side elevation of the valve; and Figs. 6 and 7, respectively, a plan view and inverted plan view of the filling-in piece.

My invention relates to an improved mode 20 of attaching screw-stems to valves by means of the revoluble joint herein described, so as to permit said stem to receive a rotatory motion without imparting a like motion to the valve; and to this end my invention consists in providing the screw-stem with a projecting circular flange formed on its lower end and adapted to engage in a suitable slotted opening formed in a hub on the upper face of the valve. A filling-in piece which fits into said 25 slotted opening forms a complement for the bearing for the upper surface of the annular flange of the screw-stem, and is retained in place by means of a spring-clamp, as herein-30 after fully set forth.

As represented in the drawings, A is the screw-stem, having on its lower end a projecting circular flange, a , made concentric to the neck a' of said stem. The valve B may be made of any required form and size, and 40 has on its upper face a central hub, b , in which the slotted opening b' is formed. Said slotted opening has at its inner end a concavity that is concentric to the central axis of the valve, and is fitted to receive the lower end of the screw-stem A. Said opening is cut radially 45 through one side of the hub b , and has an undercut enlargement, b^2 , which is adapted to receive the flange a of the screw-stem. A circumferential groove, b^3 , is formed around the

hub b , for the purpose of receiving a spring-50 clamp, as hereinabove described. The filling-in piece C is adapted to fit into the slotted opening b' , and is provided with tongues c , which engage in the enlargement b^2 . The concavity c' at the inner end of said filling-in piece conforms to and is the complement of the concavity at the inner end of slotted opening b' , so that when said filling-in piece is adjusted to its place a circular opening will be formed for receiving the neck and circular flange of the screw-stem A in such manner that the latter can be rotated in said opening with perfect freedom. The outer end of the filling-in piece C conforms in every respect to the circumferential form of the hub b . The 65 spring-clamp D is made of wire in the form of a ring having a radial separation at one side and of a suitable size to fit into the groove b^3 in such manner as to retain the filling-in piece C securely in place in the slotted opening b' 70 of the valve. When preferred, a binding-wire which has no resilient action may be substituted for said spring-clamp. With this form of revoluble joint the upper face of the flange a has an unbroken bearing around its 75 entire surface, the parts being fitted with sufficient freedom to permit the screw-stem to revolve after the valve has touched its seat, without imparting a rotatory motion to the valve, all danger of any abrasive action between the valve and its seat is avoided. 80

I claim as my invention—

The combination, with a screw-stem, A, provided with a circular flange, a , as herein described, of a valve, B, provided with a central hub, b , having a slotted opening, b' , with an undercut enlargement, b^2 , formed in one side of said hub, a filling-in piece, C, adapted to fit into the slotted opening b' , and form a complement to the concavity of the inner end 85 of said opening, and a circular clamping device for securing said filling-in piece in the slotted openings b , substantially as and for 90 the purpose herein specified.

JAMES H. BLESSING.
